UNITED STATES PATENT OFFICE.

JOHN H. BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,298,868.

Specification of Letters Patent.

Patented Apr. 1, 1919.

Application filed May 16, 1916. Serial No. 97,764.

To all whom it may concern:

Be it known that I, JOHN H. BELL, a subject of the King of Great Britain, residing at East Orange, in the county of Essex and 5 State of New Jersey, have invented certain new and useful Improvements in Telegraph Systems, of which the following is a full, clear, concise, and exact description.

This invention relates to improvements 10 in telegraph systems, and more particularly to improvements in equipment whereby an operator who may be receiving a message is enabled to signal or interrupt an operator who may be sending such message. In telegraph working, such operations are commonly termed "break" or "breaking" service, and are frequently found necessary in the handling of telegraphic communications, all as well understood in the art.

20 The principal object of this invention is to provide an improved and simplified equipment for enabling "break" operations to be performed in connection with telegraph working over lines consisting of a single section, or over lines comprising a plurality of sections, in which interworking is accomplished by means of suitable repeating equipments.

In accordance with this invention, and in 30 addition to equipment for the usual interchange of message impulse signals, a line relay and a local circuit relay are provided for each line circuit at terminal stations, and a line relay for each line is also provided 35 at repeating stations for transmitting or receiving break service impulse signals. The relays for break service are adapted to remain inert under currents of such strength as suffice for the transmission of telegraphic 40 signals. When it is desired to interrupt a sending station, however, a break key is operated at a receiving station, thereby causing currents of greater strength to flow through the various circuits to operate the 45 break relays, and the contacts of such a relay at the station which may be sending serves to disconnect the transmitting devices thereof.

This invention is illustrated diagrammatically in the accompanying drawing, in which 50 Figure 1 illustrates an equipment suitable for a telegraph terminal station, and Fig. 2 illustrates an equipment suitable for a telegraph repeating station.

55 The features of this invention may be

readily understood from a description of the operation of the system. Therefore, the various steps by which telegraphic signals may be transmitted, received and interrupted by breaking at a station receiving 60 will now be described.

Referring to Fig. 1 of the drawing, let it be assumed that this terminal station equipment is typical of an equipment at a distant station (not shown), connected in a similar 65 manner to a main line circuit or section indicated by the reference character 1. Let it be further assumed that a signal transmitting key 18 is being operated to send a message to the distant station. At each closure 70 of the key 18, a circuit is established which may be traced from a grounded battery 6, the contacts of a relay 7, thence through the serially connected windings of relays 8, 11, 14, a sounder 17, the key 18 and a resist- 75 ance unit 19 to the earth connection. The current through this circuit is of sufficient strength to operate the relays 11 and 14 and the sounder 17, but owing to the presence of the resistance unit 19, it is not strong enough 80 to operate the break relay 8. Therefore, at each closure of the key 18, a circuit is completed from a grounded source of negative current, indicated by the conventional sign, 85 over the contacts 16 of the relay 14, the contacts 13 of the relay 11, the winding of the relay 7, the contacts 9 of the relay 8, from which point it reaches the distant station by way of the line conductor 1. The equipment at the distant station corresponds with 90 the equipment at the station shown. Therefore, at that point, the impulse of negative current continues over a circuit corresponding to the contacts 9 of the relay 8, the winding 95 of the relay 7, the contacts 12 of the relay 11, and the winding of a polarized relay 20, to the earth connection. The result of this current action at the distant station corresponds with the operation of the relay 20 to close its contacts 21, and thereby include 100 a source of current 22 to operate a receiving sounder 23. The relay 14 is adapted to operate quickly and to release quickly, while the relay 11, although operating quickly, is 105 adapted to release slowly. Therefore, during the periods the key 18 is open in the sending processes, the relay 11 remains operated to continuously maintain its contacts 13 closed; while under such open moments at the key 18, the transmitting relay 14 re- 110

leases, thereby closing its contacts 15 to connect a source of grounded positive current, indicated by the conventional sign, through the circuit already traced to the line conductor 1. The sounder 17 responds to each change of current action set up by the key 18, and serves as a pilot for sending sounder by which the sending operator may involuntarily check the message being transmitted.

For convenience in describing the working of a break operation, let it now be assumed that a message is being transmitted from the distant station, and, through the response of the polarized relay 20 and the resulting operation of the sounder 23, that this message is being received at the station shown. Assuming that the operator at the last mentioned station desires to instantly attract the attention of the sending operator in order, say, to request that a letter or word be repeated, the receiving operator depresses a break key 25. This key completes the same circuit already described as controlled by the key 18, except that the resistance unit 19 is not at this time included. The omission of the resistance 19 accordingly reduces the resistance of the circuit through the relays 8, 11, 14 and the sounder 17, whereupon the resulting increase in current from the battery 6 causes the operation of the marginally adjusted relay 8; the separation of the contacts 9 of this relay disconnects the receiving relay 20, and the closing of its contacts 10 connects a source of grounded positive current, indicated by the conventional sign and of relatively high potential, with the line circuit 1. At the distant station, which is assumed to be sending at this time, current from the high pressure source completes circuit over a path which, for convenience, may be considered as corresponding with the contacts 9 of the relay 8, the winding of the relay 7, the contacts 13 of the relay 11, thence to the two-way contacting armature of a transmitting relay 14, thence to earth through either the positive or the negative source of grounded current, according to the position of the armature of the relay 14, with respect to its contacts 15 or 16 at the instant the break current arrives. The voltage of the positive break current source is sufficiently high, even in case it is opposed by the regular positive signaling current at the distant or sending station, to cause a current of such strength to flow through the marginally adjusted break relay, corresponding to the relay 7, to cause its operation for disconnecting a local transmitting circuit corresponding with the battery 6, the relays 8, 11 and 14, the sounder 17, the key 18 and the resistance unit 19. Cessation of action in the sending sounder at the distance station constitutes an indication or notice that the station receiving desires to send, which operation may take place in the usual

way after the first sending operator has released the transmitting key.

In adapting this break service for use in connection with line circuits operating through repeating equipments, a clear understanding of such a system may be had by assuming that the line circuit of the terminal station set shown in Fig. 1 is connected with a line conductor 2 of the repeating set shown in Fig. 2, while the line circuit 3 of this repeating set may be assumed as extending to a distant station (not shown), at which the terminal equipment corresponds with that shown in the Fig. 1, and the conductor 3 is thereat connected to a line circuit conductor corresponding with the line 1. Signals transmitted from the station (Fig. 1) reach the repeating equipment over the line conductors 1 and 2, thence continuing over the contacts 31 of a break relay 30, a conductor 34, the winding of a marginally adjusted break relay 36, which winding is, for convenience of adjustment, shunted by a resistance unit 39, the contacts 41 of a relay 40, a conductor 43, the winding of a quick operating, slow-releasing universal current relay 45 and the windings of a polarized relay 48 to an earth connection. In response to the alternate changes of current polarity set up by the transmitting relay 14, under control of the sending key 18, the polar relay 48 selectively moves its armature to correspondingly include the associated grounded sources of positive and negative current to complete a circuit, which may be traced from the armature of this polar relay 48, the contacts 47 of the relay 45, the winding of a marginally adjusted break relay 30 (the winding of this relay is for convenience of adjustment, shunted by a resistance unit 33) a conductor 35, the contacts 37 of the relay 36 to the line circuit 3, over which it reaches the distant station and is received by means of a polar relay and sounder, respectively corresponding with 20 and 23 of Fig. 1. In a converse manner, messages transmitted in the opposite direction, that is, from the distant station to the station Fig. 1, set up current impulses which reach the repeating equipment over the line circuit 3, thence traversing the contacts 37 of the relay 36, a conductor 35, the winding of the relay 30, the contacts 46 of the relay 45, a conductor 44, the winding of the quick-operating slow-release universal current relay 40, and the windings of a polarized relay 52, to an earth connection. Changes of current direction, as set up through the polarized relay 52 by the message impulses transmitted from the distant station, cause this relay to respond thereto, and alternately connect the associated grounded sources of positive and negative current to the armature of this relay. From this armature, these current impulses traverse the contacts 42 of the relay 40, the

winding of the relay 36, the conductor 34, the contacts 31 of the relay 30, thence over the main line conductors 2 and 1 to the receiving circuit already traced at the first 5 station, Fig. 1, at which point the polarized relay 20 operates the sounder 23 to reproduce the message. Assuming now that this station, Fig. 1, desires to attract the attention of the distant sending operator, the break 10 key 25 is depressed to operate the marginally adjusted relay 8, which thereupon switches the line 1 from the receiving circuit to the high potential source of break current. This break current then traverses 15 the line conductors 1 and 2, the contacts 31 of the relay 30, the conductor 34, the winding of the relay 36, the contacts 42 of the relay 40 (this relay is operated at this time, due to message impulses from the distant 20 station), thence to the armature of the polar relay 52, from which point, the break current completes circuit to earth through either one of the associated grounded sources of signaling current, according to the position 25 of this polarized armature at the instant the break current arrives. The marginally adjusted relay 36 receives a sufficient wattage from the break current to cause it to operate, thereby switching the line circuit 3 from the 30 repeater equipment at the separated contacts 37, and, through the contacts 38, connects this line circuit directly to a grounded source of high potential positive break-current, indicated by a conventional sign at this 35 relay. This repeated break current reaches the distant station by way of the line circuit 3, and thereat operates a relay corresponding with the relay 7 to disconnect the local transmitting devices, as already described for single section working. The operations at the repeating station which take 40 place when the distant station interrupts a message, being transmitted from the station (Fig. 1), are set up by the high potential 45 break current from the line 3 traversing the contacts 37 of the relay 36, the conductor 35, the winding of the break relay 30, the contacts 47 of the relay 45, (this relay is held operated at this time by message impulses 50 from the station, Fig. 1), to the armature of the polar relay 48, from which point the circuit is completed through the associated source of signaling current with which this armature may at the moment be connected. 55 The resulting incremented current through the relay 30 causes it to operate, and through the separation of its contacts 31 and the closing of its contacts 32, respectively, switches the line conductor 2 from the repeating 60 equipment and connects it directly to a grounded source of high potential break current, suitably indicated at this relay. From this point, the break current reaches the station (Fig. 1) by way of conductors 2 and 1, 65 and operates the relay 7 to disconnect the

transmitting devices as already described for single section working.

From the foregoing description, it will be apparent that, on a single section two-way telegraph line, the marginal local circuit relay 8, under control of the break key 25, controls a distant marginally adjusted line relay 7, to disable the sending equipment at such distant station. And also that in the repeating equipment, while the relays 45 and 70 48 comprise a group for repeating message signals from the line 2 into the line 3, the marginally adjusted line relay 36 serves to repeat high potential break currents from the line 2 into the line 3, and conversely, the 75 line relays 40 and 52 at the repeating station operate to repeat message signals from the line 3 into the line 2, while the marginally adjusted line relay 30 operates to repeat high-potential break currents from the line 80 3 into the line 2.

Referring to my pending application, Serial No. 63251, filed Nov. 24, 1915, for a telegraph system, it will be understood that the terminal station or repeating station 90 equipments therein disclosed may be used interchangeably with the equipments disclosed in the present application. From the descriptions already made in connection with these applications, the operations and actions taking place with interchanged arrangements for working the equipments of the two systems would be readily apparent to a person skilled in the art. Therefore, it is considered that descriptions of such proposed working are accordingly unnecessary. 95

What is claimed is:

1. In a telegraph system, a transmitting apparatus, a line associated therewith, a source of normal operating current, a source 105 of abnormal operating current, a relay in circuit with said transmitter, said relay being responsive only to abnormal current, circuit breaking means between said line and said sources of current and controlled by 110 said relay, and means for impressing abnormal current on said relay to operate said current breaking means and put abnormal current on the line.

2. In a telegraph system, a transmitter, a 115 receiver, and a line, a relay in said transmitter responsive to abnormal current, means in said line controlled by said relay to put abnormal current on said line, a relay in said line responsive to abnormal 120 current, means in said transmitter controlled by said last mentioned relay to open the circuit of said transmitter.

3. In a telegraph system, means for transmitting and receiving telegraphic messages, 125 means in circuit therewith for repeating said messages, local and line relays co-operating with said repeating means, said relays being unaffected by the normal operating current, a source of break service current operated 130

with said repeating means, means controlled by said relays for simultaneously opening the circuit to said repeating means and for impressing said break service current on a line, and means for controlling said relays to operate said relay with said control means.

4. In a telegraph system, a line, a transmitter, a receiver, and repeating stations connected therewith, a plurality of current sources at each station, means responsive to

operating current to impress said current sources on the line, a source of break-service current at each station, switching means adapted to put said break service current on the line, means at each station responsive to abnormal current to operate said switching means, and means for controlling said switch operating means.

In witness whereof, I hereunto subscribe my name this 12th day of May, A. D., 1916.

JOHN H. BELL.
